UNITED STATES PATENT OFFICE

FRANCESCO S. GENOVESE, OF JAMAICA, NEW YORK

LIFE PRESERVER

Application filed May 13, 1932. Serial No. 611,176.

This invention relates to life preservers and has for an object to provide an improved construction wherein the same may be readily applied or removed and not appreciably deteriorate during use and for a long time when unused.

Another object of the invention is to provide an improved life preserver which may be quickly secured around the waist, and, if desired, supported by the shoulders, the structure including flexible metallic sections for carrying metallic floats.

An additional object, more specifically, is the provision of a life preserver formed of different shaped metallic floats removably mounted on sections of a band or belt, the arrangement being such that the band or belt may be fastened around the body of a person quickly when the preserver is to be used.

In the accompanying drawing,

Figure 1 is a plan view of a life preserver disclosing an embodiment of the invention.

Figure 2 is a fragmentary edge view showing slightly more than one of the units illustrated in Figure 1.

Figure 3 is a rear view of a slightly modified form of life preserver to that shown in Figure 1.

Figure 4 is a plan view with certain parts broken away illustrating slightly more than two units of the structure shown in Figure 3.

Figure 5 is an elevation of another modified form of the invention wherein hollow metallic balls are removably connected to a supporting chain.

Referring to the accompanying drawing by numerals, 1 indicates what may be termed a belt or band, the same being made of a number of flat plates or strips 2 of metal, having their ends 3 and 4 turned over to produce eyes through which the respective links 5 extend, thus connecting the various plates. To augment and re-enforce the link 5, a pair of rings 6 is arranged at each juncture of the respective plates 2 so that in case one or more rings should break or come loose, there will be enough left to hold the parts together. Suitable rings 6 are

mounted at one end of the belt while snap fasteners 7 are connected to the other end of the belt through springs 8. It will be evident that the springs 8 may be of any strength and also any length so as to permit the preserver to be mounted on persons of different sizes.

As illustrated particularly in Figure 2, there is a float 9 on each plate 2, said float being made from metal and hollow so as to produce a desired floating action when in use. An ear 10 is formed either integral with the float 9 or rigidly secured thereto and extending through an aperture 11 in plate 2, after which the ring 12 is mounted in the ear so as to lock the float on the plate 2. In this way all the floats are removable and in case any one should become damaged, it can be removed and a new one substituted so that damage to part of the life preserver will not necessitate throwing the entire preserver away, but only the injured parts.

In Figure 3, substantially the same structure is shown as that shown in Figure 2, but the floats 13 are oval in cross section, as shown in Figure 4, and comparatively long so as to secure a better floating action. Also, there are provided a number of bands 14 connected by loops 14' and links 5', each float 13 having three ears 15 on each side 89 accommodating certain of the rings 16. A metallic shoulder strap 17 and back strap 17' are also provided and connected in any suitable manner with certain of the floats so that the shoulder straps may be fitted over the shoulders of the person using the life preserver, while hooks 7' may be used to clamp the various belts around the person.

Where the person expects to stay in the water some time, the arrangement shown in Figure 3 is preferable as it gives a better floating action by reason of the size of the floats 13, but, if desired, the floats 9 could be made large enough to secure whatever floating action the person might wish.

In Figure 5 a further modified form of the invention is shown wherein hollow metallic balls 18 are utilized, the same being connected by snap fasteners 19 to a chain 20, which chain may be clamped around the

waist of a person by a snap fastener 21. While this form of the invention may be used as a regular life preserver, it is also adapted for use in learning how to swim and for timid persons in bathing, as it will support either all of the body or part of the body in water, and thereby permit a person to learn how to swim more readily. It is understood, of course, that the amount of buoyancy is determined by the size of the balls 18 in comparison to the weight.

I claim:—

1. A life preserver comprising a belt section formed from a plurality of plates, means for hingedly connecting the plates together, each plate having an aperture therein, a hollow metallic float mounted on each plate, each float having an apertured

ear extending through the aperture in the plate, and a ring mounted in the apertured ear for locking the float in position.

2. A complete metal life preserver comprising a plurality of bands, each band having a plurality of independent plates, each plate having a substantially centrally positioned aperture said plates being articulated, means for connecting the ends of said bands together when the preserver is in use, a single float for one plate of each band, each of said floats having ears adapted to extend through the apertures in said plates, removable locking members extending through said ears for removably locking said floats in position, and a pair of shoulder straps connected with certain of the floats.
